UNITED STATES PATENT OFFICE

154,252

DESIGN FOR A SWEATER OR SIMILAR ARTICLE

Bernard Ehrenreich, New York, N. Y.

Application September 17, 1948, Serial No. 148,631

Term of patent 3½ years

(Cl. D3—4)

To all whom it may concern:

Be it known that I, Bernard Ehrenreich, a citizen of the United States of America, residing in New York, county of New York, and State of New York, have invented a new, original, and ornamental Design for a Sweater or Similar Article, of which the following is a specification, reference being had to the accompanying drawing, forming part thereof,

The figure on the drawing is a front view of a sweater or similar article, showing my new design. The opposite side of the sweater is substantially plain.

The dominant feature of my design resides in the portions shown in solid lines.

I claim:

The ornamental design for a sweater or similar article, substantially as shown and described.

BERNARD EHRENREICH.
